CLAIM

The ornamental design for a display screen or portion thereof with graphical user interface, as shown and described.

DESCRIPTION

FIG. 1 is a front view of a display screen or portion thereof with graphical user interface showing our new design according to a first embodiment;

FIG. 2 is a front view of an electronic device having a display screen with the graphical user interface of FIG. 1 applied to the display screen;

FIG. 3 is a front view of a display screen or portion thereof with graphical user interface showing our new design according to a second embodiment; and,

FIG. 4 is a front view of an electronic device having a display screen with the graphical user interface of FIG. 3 applied to the display screen.

The outermost broken lines in the figures show a display screen or portion thereof, or an electronic device having a display screen, and form no part of the claimed design.
